UNITED STATES PATENT OFFICE.

WILLIAM F. HOSFORD, OF OAK PARK, ILLINOIS, ASSIGNOR TO WESTERN ELECTRIC COMPANY, INCORPORATED, OF NEW YORK, N. Y., A CORPORATION OF NEW YORK.

WIRE-TINNING MACHINE.

1,346,825.

Specification of Letters Patent. Patented July 20, 1920.

Application filed March 25, 1918. Serial No. 224,508.

To all whom it may concern:

Be it known that I, WILLIAM F. HOSFORD, a citizen of the United States, residing at Oak Park, in the county of Cook and State 5 of Illinois, have invented certain new and useful Improvements in Wire-Tinning Machines, of which the following is a full, clear, concise, and exact description.

This invention relates to wire tinning machines, and more particularly to wire tinning machines similar to that disclosed in the Patent No. 1,248,107 issued November 27, 1917, to J. D. Hathaway and to which reference may be had for a description of 15 the general features of the process and apparatus.

The object of this invention is to produce a machine of this character which will be very compact in structure, efficient in operation, and capable of tinning a large number of separate strands of wire simultaneously.

One of the features of this invention resides in the construction, combination, and 25 assembly of parts whereby all of them may be embodied in a single compact structure on one supporting frame. In accordance with this feature of the invention, wire supplying spools are mounted on the side of 30 the frame near one end, take-up reels and winding mechanism on the same side of the frame near the opposite end, and the acid, tin, and cooling baths are mounted upon the top of the machine in a position 35 to be easily accessible to the operator. The wire supply reels at one end of the frame are mounted in a staggered relation in the same horizontal plane and the take-up reels at the other end of the frame are mounted 40 in a similar relation to each other, thus making these reels easily accessible and non-interfering.

A further feature of the invention relates 45 to the means for assembling into a small space, with all parts easily accessible for efficient operation, the apparatus for tinning simultaneously a large number of separate strands of wire. In accordance with this feature of the invention, complete tinning apparatus is provided upon opposite sides of the same frame, each apparatus being capable of handling simultaneously a plurality of wires, the number of wires han-

dled upon each side of the frame being such as can be efficiently managed by one 55 operator.

As a further feature of this invention, each strand of wire is carried through the tinning bath through the agency of an individual pivotally supported and weighted 60 arm which is automatically swung upward about its pivot when released to receive the wire which is to be fed through the bath. This combined with the non-interfering arrangement of the supply and take-up reels 65 enables an operator to replace an empty supply reel or take care of a broken strand without interrupting the tinning operation of the remaining strands and without inconvenience or danger. 70

Another feature of this invention is the combining of the pivotally supported arms into a sectional cover for the tinning bath which prevents the oxidation of the molten tin and confines the fumes which would 75 otherwise have to be carried away by means of a hood.

In the drawings—

Figure 1 is a view in front elevation of the machine; 80

Fig. 2 is a plan view thereof;

Fig. 3 is a longitudinal section in dia- 85

grammatic form on the line 3—3 of Fig. 1;

Fig. 4 is a plan view of the tinning bath, and

Fig. 5 is a vertical section on the line 5—5 thereof.

As illustrated in Figs. 1 and 2, the complete machine is composed of two independently operated and driven machines carried 90 upon a single supporting frame 10 built from two similar side frame members 11 and 12 and end standards 13 and 14. Intermediate the end standards 13 and 14 is a standard 15, which acts as a central support for the machine and also supports motors 16 and 17. Fastened to the side frames 11 and 12 at one end thereof and near the top are brackets or tables 18 and 19 which serve to directly support acid, tinning, and 95 cooling baths, and also air wipers.

In the preferred form of the invention as illustrated in the drawings and to be described hereafter, each independent machine handles simultaneously five strands of wire, 100 each strand being run from a supply spool 105

through the acid, wiping, tinning, and cooling operation and around a capstan and take-up reel independently of the others. As the construction and operation of each 5 machine is similar, a description of one of the machines will be sufficient.

The motor 17 which is mounted from the central support 15 drives the machine mounted on the side frame 12. The motor 10 shaft has a pinion 20 which in turn drives a link chain 21 connected to a gear 22 on the main drive shaft 23. The main drive shaft connects with suitable gearing which drives the capstans 24. This main drive shaft also 15 carries a pinion 25 which in turn meshes with a gear 26 mounted directly below on a shaft suitably journaled from the side frame 12. This last mentioned shaft at the other end thereof has the gear 27 meshing with a link chain 28 driving a suitable reversing mechanism 29. A shaft 30 extends from the reversing mechanism and has mounted thereon pinions 31. The object 20 of this reversing mechanism will hereafter 25 be described in connection with the take-up reels. Any suitable reversing mechanism may be used in which the motion of rotation of its main driving shaft is reversed at regular intervals.

30 Mounted in a staggered relation on the same horizontal plane and set at increasing widths from the longitudinal center line of the machine, at one end of the side frame 12 and about intermediate the height of the 35 machine, are brackets 35 carrying wire supplying spools 36. The brackets 35 are equipped with brake or tension devices as illustrated in Fig. 1, upon which the wire acts while passing from the supply spools.

40 This brake consists of a bell crank lever 37 pivoted at the bottom of a bracket 35 and carrying a sheave 38 at its outer end under which the wire passes. Attached to the lever 37 by a yielding connection intermediate 45 at its pivot and the sheave 38 is a round leather belt 39, which passes over a grooved sheave 40 mounted fast on the wire supply spool shaft and in the rear of the wire supply spool 36, the end being attached to the bracket 35. The belt is held tightly in the 50 groove of the sheave 40 by a spring 41 acting against the long arm of the bell crank lever 37.

The object of this brake is to stop the 55 spool 36 from overrunning and unwinding the wire in case the wire breaks, in which case the lever 37 would drop, due to the action of a spring 42 one end of which is attached to the short arm of the bell crank 60 lever 37, the other end resting against the bracket 35. This will result in the tightening of the belt 39 in the groove of the sheave 40, the belt otherwise being held loosely in the groove with no braking effect on the 65 spool, due to the action of the wire being

run through the machine which slightly raises the lever 37.

From the sheave 38 the wire passes up and over suitable guiding sheaves 45 and 46 and enters the acid bath where, by passing 70 between layers of felt soaked in a suitable acid and under pressure of a cover 48, the wire is cleaned of all dirt, grease, and oxid.

The wire after passing from the acid bath passes through the air wiper 49 which dries 75 the wire. This air wiper consists of a pipe 50 with nozzles 51 which spray a jet of compressed air on the wire as it passes between them, as best illustrated in Fig. 2.

From the air wiper the wire passes over 80 the guiding sheaves 52 and into the tin bath 55, as best shown in Figs. 4 and 5. As shown, the tin bath 55 consists of a hollow metal container 56 for the holding of the liquid tin, and is set into a chamber formed 85 in the bracket 18. The container 56 is provided with a flange 57 by means of which it is fastened to the bracket or table 18. Placed directly below the container 56 is an electrical heating element 58 consisting 90 of a number of turns of high resistance wire embedded in a housing 59 of any suitable cement. Connected to the electrical heating element in a suitable manner are the conductors 60 and 61 leading from a source 95 of current. Below the electrical heating element 58 with its housing 59 the chamber is packed full of a suitable heat insulating material. This arrangement of putting in a heat resisting material under the electrical heating element and a heat conducting substance above the heating element forces all the heat upward and into the tin bath, and results in greater efficiency in the operation 100 thereof.

Spanning the opening in the container 56 are a series of levers 65, 65. These levers 65 and side pieces 66 and 67 form a cover for the tin bath and are pivoted at one end to a shaft 68, this same end terminating also in 110 an arm 69 to which is pivoted a rod 70 passing through a suitable opening in the bracket or table 18. Attached to the rod 70 is a counter-weight 71. The other end of the levers 65 have attached thereto an upwardly 115 and outwardly extending lug 72, and pivoted at the end thereof is a handle member 73. The lower part of the handle member 73 is latch shaped so as to lock into a notch 74 cut into a rod 75 which extends across the 120 width of the five levers 65 and is supported in bearings 76 and 77 carried by the container 56. Near the center of the lever 65 an arm 80 extends down into the container 56 and is equipped with a sheave 81 under 125 which the wire passes. Near its pivot the lever 65 contains a sleeve 82, in which a holder 83 for a diamond die is mounted. The position of the sleeve 82 is such that the die is partly immersed in the molten tin. 130

As the wire passes through the die the excess tin is removed, leaving a thin coating, while at the same time the wire is slightly drawn in order to keep a uniform size.

- 5 An opening is formed in side piece 66 of the tin bath connecting with a flue 100, shown in dotted lines in Fig. 2, which also connects with a corresponding side piece on the other machine. The object of this flue 10 is to carry off any fumes arising from the fluid tin.

To thread the wire through the tin bath the operator releases the latch from the bar 75 which will allow the lever 65 to turn upon its pivot, due to the action of the counter-weight 71, and move upward, carrying the sheave 81 and the die holder 83 which is partly immersed in the fluid tin. This allows the operator to quickly thread the wire 20 through the holder 83 carrying the die. This threading operation occurs whenever the operator replaces an empty supply reel or takes care of a broken strand. The operator in bringing the lever down again 25 turns it about its pivot against the action of the counter-weight 71 and replaces the latch in the notch 74 in the rod 75, the wire entering underneath the top of the levers through a slot 84 in the end wall thereof.

30 The five levers 65 forming together with the side pieces 66 and 67 a complete cover for the tin bath and each lever being pivoted separately, results in a very efficient construction, in that the opening made by the 35 raising of one lever does not seriously lower the temperature of the fluid tin and does not interfere with the tinning of the other strands.

After emerging from the tin bath the 40 tinned wire passes over the guide sheaves 85 mounted on the shaft 68 into the cooling bath 86 which consists of a shallow metal box containing running water. This box is slotted at each end and is fitted with felt 45 pads covering these slots. The wires run through slots in the felt pads which are used to raise the water level above the wire, the surplus water being removed from the wire by an air wiper 87 immediately upon leaving 50 the cooling bath. This air wiper 87 is similar to the previously mentioned air wiper 49 used in connection with the acid bath 47.

After passing the air wiper 87 the wire is wound several times around the capstan 24. 55 The capstans 24, 24 are located at the opposite end and near the top of the side frame 12 on which the wire supplying spools are mounted, and are set at increasing widths from the longitudinal center line of the machine in reverse order to that of the wire supplying spools. The capstans 24, 24, as previously mentioned, receive their motion through suitable gearing from the main drive shaft 23. Each capstan is engaged or disengaged at will by the operator through a

separate and suitable disk clutch mounted on the capstan shaft and operated by the levers 90 attached to the front part of the machine.

From the capstan the wire passes through the distributing mechanism 91 consisting of 70 guide sheaves 92 properly mounted from a gear rack 93. The gear rack 93 receives motion from the pinion 31 carried by the shaft 30 which receives its motion from the reversing mechanism 29. The object of this reversing mechanism is to continuously reverse the motion of the shaft 30, thereby moving back and forth the rack 93 carrying the guide sheaves 92 which will serve to distribute the wire uniformly over the surface of a take-up reel 94. The take-up reels are located just below the distributor mechanism and are each driven by separate and suitable gearing each controlled by a separate disk clutch mounted on the capstan 85 shaft, thereby maintaining the same peripheral speed between the take-up reel 94 and the capstans 24.

What is claimed is:

1. In a machine for tinning a plurality of 90 separate wire strands simultaneously, a main supporting frame, a set of supply spools mounted on one side of said frame at one end thereof, a second set of supply spools mounted upon the opposite side and 95 end of said frame from the first-mentioned supply spools, a set of take-up reels for each set of said supply spools mounted upon opposite sides of said frame, and a pair of tinning apparatuses mounted upon opposite 100 sides of said frame.

2. In a machine for tinning a plurality of separate wire strands simultaneously, a main supporting frame, two sets of wire supply spools mounted at opposite ends and 105 upon opposite sides of said frame, the spools of each set being horizontally staggered with respect to each other, two sets of take-up reels mounted upon opposite sides of said frame and at ends opposite the supply spools 110 the reels of each set being horizontally staggered with respect to each other to correspond with the staggering of the supply spools, and a tinning apparatus for each set of said supply spools. 115

3. In a machine for tinning a plurality of separate wire strands simultaneously, a main supporting frame, a complete tinning apparatus mounted upon each side of said frame each tinning apparatus comprising a 120 set of supply reels mounted upon the side of the frame at one end thereof, a set of take-up reels mounted upon the side of the frame at the opposite ends thereof the spools and reels being horizontally staggered with respect to each other, a tinning bath, and a driving mechanism for the take-up reels. 125

4. In a machine for tinning a plurality of wires simultaneously, a main supporting frame comprising a pair of side members ta- 130

1. tapered from the center toward each end and each side member being provided with longitudinally staggered surfaces, a center member and end members connecting said side members, a set of supply spools and a set of take-up reels mounted upon each of said side members, a tinning apparatus mounted upon each side of said frame and upon opposite sides of said center member, and driving apparatus for each set of take-up reels mounted between said side frame members.
5. In a machine for tinning a plurality of separate wire strands simultaneously, a frame for supporting separate machines comprising side members equipped with a plurality of side faces in a staggered relation, supply and take-up reels mounted on said side faces in non-interfering relation below the tinning apparatus, and end standards for connecting and supporting said side members.
10. In a machine for tinning a plurality of separate wire strands simultaneously, a frame for supporting two separate machines comprising similar side members equipped with a plurality of stepped vertical faces at each end thereof, supply and take-up reels mounted in non-interfering relation below the tinning apparatus on said vertical faces, and end standards for connecting and supporting said side members.
15. In a machine for tinning a plurality of separate wire strands simultaneously, a frame for supporting separately driven machines comprising two similar side members each of said members supporting one of said machines and equipped with a plurality of stepped vertical faces at each end thereof, supply and take-up reels mounted in non-interfering relation below the tinning apparatus on said stepped faces, end standards for connecting and supporting said side members, a center standard for supporting driving means for said machines and as an additional connecting and supporting means for said side members, and driving means supported upon said center standard.
20. In a machine for tinning a plurality of separate wire strands simultaneously, a frame, tinning apparatus mounted upon said frame, means for guiding each strand individually through said tinning apparatus said means also forming a covering for said tinning apparatus and comprising a series of latch released members adapted to move upward automatically upon being unlatched.
25. In a machine for tinning a plurality of wire strands simultaneously, a frame, tinning apparatus mounted upon said frame, means for guiding each strand individually through said tinning apparatus said means also forming a covering for said tinning apparatus and comprising a series of latch released, fulcrumed and weighted levers adapted to automatically turn upon their fulcrum upon being unlatched to raise the guide from the tinning apparatus.
30. In witness whereof, I hereunto subscribe my name this 14th day of March, A. D. 1918.
35. WILLIAM F. HOSFORD.
